UNITED STATES PATENT OFFICE.

HARRY W. HUNTRRESS, OF TURLOCK, CALIFORNIA.

BANK-WINDOW SHIELD.

1,423,327.

Specification of Letters Patent.

Patented July 18, 1922.

Application filed June 22, 1920. Serial No. 390,787.

To all whom it may concern:

Be it known that I, HARRY W. HUNTRRESS, a citizen of the United States, residing at Turlock, in the county of Stanislaus and State of California, have invented certain new and useful Improvements in Bank-Window Shields; and I do hereby declare the following to be a full, clear, and exact description of the invention, such as will enable others skilled in the art to which it app-
10 pertains to make and use the same.

This invention has relation to certain new and useful improvements in a bank window shield and has for its primary object the im-
15 provement of the shield in front of and around the window of a paying teller or other clerk in a bank or the like.

Another object of the invention resides in the provision of a shielding construction of
20 plates which will thoroughly protect and conceal a party handling money and other valuables, mirrors or reflecting members being included in the shield construction and arranged so that the party dealing with the
25 protected one and the protected party may readily see the reflected images of one another.

The invention has for a further object, the provision of a window shield of the above
30 stated character which will be of simple construction and arrangement and yet which will prevent the protected party from being injured in any manner by a party on the other side of the window.

35 The invention has for a further object, the provision of a window shield of the above stated character which will be highly effi-
cient in use and in which the main solid front shield member will be provided with
40 a door which may be opened at times by the protected party for the passage there-
through of bulky packages.

With the foregoing and other objects in view as will appear as the description pro-
45 ceeds, the invention consists in the construc-
tion, combination and arrangement of co-
operating elements as hereinafter more spe-
cifically set forth, claimed and shown in the
50 accompanying drawings and in which:

Figure 1 is a front elevation of the bank window provided with the shield forming the subject matter of the present invention.

Figure 2 is a vertical sectional view there-
55 through on the plane of line 2—2 of Figure 1, looking in the direction indicated by the arrows.

Figure 3 is a horizontal sectional view on the plane of line 3—3 of Figure 1, looking in the direction indicated by the arrows.

Figure 4 is a detail view of the main front 60 shield member, removed, to show the con-
struction thereof.

Referring more in detail to the drawings in which similar reference characters designate corresponding parts throughout the sev-
eral views, 1 indicates the counter or shelf back of the window 2. To either side of the counter or shelf 1 are located solid side shield members 3 which extend upwardly and which are securely fastened to the coun-
ter or shelf 1. Securely fastened by its 65 lower corners to the counter or shelf 1 is the main front solid shield 4 which has a central portion of its lower end spaced slightly above the counter or shelf 1 to pro-
vide the passageway 5 through which money and the like may be passed to and from the bank clerk back of the counter or shelf 1. The main shield member or shield 4 is pro-
vided with a door 6 in its central portion 70 which is hinged on the inner side of the member 4, as shown at 7, and has a suitable latch or lock on its inner side, as shown at 8. The door 6 may be opened when nec-
essary to pass packages through the window. 75 The door can only be operated by the party back of the counter or shelf 1, however, as it will be impossible for the latch 8 to be released from in front of the main shield 4,
owing to the vertical longitudinal edge or 80 side portions 9 thereof directed at an angle to the main portion thereof and toward the side shield members 3. The side portions 9 of the member 4 are also directed rearwardly 85 and terminate within a few inches of the side members 3 so as to prevent the party in front of the window 2 from reaching around the edge of the member 4 to release the latch 8 and open the door 6. Baffle plates 10 are also attached to the side members 3 slightly 90 rearwardly of the side portions 9 of the member 4 and directed toward the member 4 in planes substantially parallel with the side edges 9 of said member 4, as clearly shown in Figure 3 of the drawings. These baffle 95 plates 10 extend vertically and consist of narrow strips which are of sufficient width to overlap the edge portions 9 of said mem-
ber 4, as clearly shown in Figure 3 of the drawings, to hide the bank clerk from direct 100 view from a party in front of the window 2.

Mirrors 11 are secured to the inner face

2
of the side members 3, forwardly of the baffle plates 10 and opposite the turned edge portions 9 of the member 4. To further hide the bank clerk from direct view from in front of the window 2 and protect this party, a sill 12 is provided on the forward portion of the counter or shelf 1, a suitable distance in front of the main shield 4, and extends practically the entire length of the main portion thereof so as to prevent a party from looking beneath the member 4. This sill 12 is only a few inches high but it is sufficient to hide the bank clerk from the view of the party in front of the window 2. It will also be understood that the main shield 4 is secured at its upper corners to the side shield members 3, as shown at 13 and the upper portion 4' of the member 4 may be finished along its upper edge in any suitable manner, as shown at 4".

It will be understood that the side shield members 3 are preferably formed of sheet metal and the same is true of the main front shield 4 and the baffle plates 10 so that the party behind the front member 4 may be thoroughly protected. It is also to be noted that the shield members are placed and arranged in such a manner as to make it practically impossible if not entirely impossible for any party to pass the point of a fire arm around one or more of the shield members to injure the party back of the front shield member 4 and between the side shield members 3. Attention is also directed to the fact that in the drawings, particularly Figures 2 and 3 it will be seen that the conventional form of bank window shelf 2 has been disclosed although this may be varied as desired. It will further be evident that this construction and arrangement of shield members may be employed to protect the parties in theater box offices, cashiers of mines located in lonely places and so forth. In fact the invention may be employed to protect any parties who may require such protection while handling money or other valuables.

While the main front member is described as a solid shield 4 and shown in this manner in the drawings, it will be understood that this member may be formed as a shutter and composed of a plurality of members arranged in overlapping relation, if desired or formed in any other suitable manner.

55 It is believed the complete construction and operation of the bank window shield may now be readily understood without fur-

ther description thereof. It is further understood that while the preferred embodiment of the invention has been shown and described, minor changes in the details of construction may be resorted to within the scope of what is claimed without departing from the spirit of the invention.

65

What is claimed is:—

1. In combination with a counter, a shield rising therefrom, a side wall spaced therefrom, said shield having a door, fastening means for the door on the interior thereof and of said shield and the shield adjacent 70 said side wall extending rearwardly to protect the fastening means against unauthorized opening.

2. In combination with a counter, side walls extending above the same, a shield rising from the counter intermediate said side walls, a door on the shield, fastening means for the door operable from the interior, said shield at its sides having interiorly extending portions to protect the door against unauthorized opening and means to brace the shield from the side walls.

3. A window shield means having side walls, a shield member intermediate said walls having rearwardly deflected side portions terminating short of said side walls, baffle plates in the rear of said shield member extending inwardly from said side walls and terminating beyond the outer side edges of the side portions, said side walls having reflecting surfaces in advance of said baffle plates to permit virtual images to be viewed by a person through the spaces intermediate the said side portions and baffle plates while concealed by the shield means.

4. A window shield means having a side wall, a shield member adjacent to the same having a rearwardly deflected side portion terminating short of said side wall, a baffle plate in the rear of said shield member extending inwardly from said side wall and terminating beyond the outer side edge of said side portion, and said side wall having a reflecting surface in advance of said baffle plate to permit virtual images to be viewed by a person through the space intermediate the guide portion and baffle plate while concealed by the shield means.

In testimony whereof I affix my signature in presence of two witnesses.

HARRY W. HUNTRESS
